METHOD OF MAKING FINGER RINGS AND THE LIKE

Filed June 25, 1929

Henry W. Peters Inventor

By Cadmore & Co. Attorneys.

UNITED STATES PATENT OFFICE

HENRY W. PETERS, OF BOSTON, MASSACHUSETTS

METHOD OF MAKING FINGER RINGS AND THE LIKE

Application filed June 25, 1929. Serial No. 373,657.

This invention relates to a new and improved method of making finger rings and the like, one of the objects being to produce a ring having a stone seated therein, without the use of any separate fastening means for the stone, it being possible to produce the entire metal portion of the ring out of a single piece of metal shaped by stamping or in any other way desired, the final step of shaping the device into a ring also resulting in the clamping and retention of a stone assembled with the ring.

With the foregoing and other objects in view which will appear as the description proceeds, the invention resides in certain novel steps in the method of producing finger rings and the like and in certain novel details of construction and combinations of parts which will be hereinafter more fully described and pointed out in the claims, it being understood that changes may be made in said method and in the construction and arrangement of parts without departing from the spirit of the invention as claimed.

25 In the accompanying drawings the steps of the method and the resultant finger ring have been illustrated.

In said drawings,

Figure 1 is an edge view of a blank shaped preparatory to being fashioned into a ring, a stone to be set into the ring being illustrated adjacent thereto prior to being inserted onto its seat.

Figure 2 is a bottom plan view of the structure shown in Figure 1, the initial positions of the wings forming the sides of the signet portion of the ring being illustrated by dotted lines.

Figure 3 is a view similar to Figure 1 showing the stone positioned in the signet portion.

Figure 4 shows the completed ring.

Figure 5 is a section on line 5—5, Figure 4.

Referring to the figures by characters of reference, 1 designates the signet portion of a ring formed with an opening 2 of any desired shape from opposed sides of which are extended wings 3 adapted to be bent to form opposed walls of a recess 4. The initial positions of these wings have been indicated

by broken lines in Figure 2 while the positions assumed thereby after bending have been indicated by full lines in Figures 1 and 2.

Extended in opposite directions from the signet portion of the ring are arms 5, those ends of the arms forming opposed sides of the signet portion of the ring being formed with gripping jaws of any desired configuration indicated at 6. These jaws are spaced apart a sufficient distance to permit the insertion of a stone 7 into the recess 4 formed between the jaws and the wings 3. Opposed edges of the stone can be beveled or otherwise shaped for the purpose hereinafter explained.

The metal portion of the ring thus far described can be produced by means of dies or in any other manner desired. After the same has been shaped the stone 7 is inserted between the jaws 6 and the arms 5 are then bent toward each other and their free ends brought together to form a ring-like band 8, it being understood that the free ends of the arms are joined by hard solder or in any other manner desired. This act of bending the arms to produce the ring will result in bending the jaws 6 toward each other so that they will clamp against opposed edges of the stone 7 or the like and tightly grip the same thereby holding it securely in the signet portion of the ring so that it cannot be removed.

The foregoing has been illustrated clearly in Figure 4. The flanges 3 will of course prevent the stone from being withdrawn laterally from the signet portion.

While the means herein described for holding the stone assembled with the metal portion of a ring are particularly suitable for use in the manufacture of finger rings, it is to be understood that the same method can be followed in the manufacture of other kinds of jewelry. Furthermore, when the metal portion of the ring or the like is shaped as described by means of dies or the like, any suitable ornamentation can be formed thereon and a monogram or other ornamentation can be formed across the outer open face of the signet portion.

Although the stone 7 has been shown pro-

vided with beveled edges, it is to be understood that any suitable means may be provided whereby, when the jaws 6 are swung toward each other, they will engage and retain the stone.

What is claimed is:

1. The herein described method of producing a finger ring or the like which consists in providing a signet portion with a recess and with oppositely extending portions, inserting a stone or the like into the recess, and subsequently bending the oppositely extended portions toward each other to form a ring and contract opposed walls of the recess into engagement with the stone or the like.
2. The herein described method of making a finger ring or the like which consists in forming a single length of metal with an intermediate signet portion having a recess, inserting a stone or the like into the recess, and then bending the end portions of the strip to bring them together and to force opposed walls of the recess into engagement with the stone or the like to hold it against displacement from the recess.
3. The herein described method of making a finger ring or the like which consists in forming in a single piece an apertured signet portion having a recess and oppositely extending portions forming opposed walls of the recess, thereafter inserting a stone or the like into the recess, and finally bending the end portions of the strip toward each other to shift opposed walls into gripping engagement with the inserted stone or the like.
4. The herein described method of making an article of jewelry which consists in forming a one-piece metal strip with an intermediate recess, inserting a stone or the like into the recess, and then bending the end portions of the strip toward each other to force opposed walls of the recess into gripping engagement with the inserted portion.
5. The herein described method of making a finger ring or the like which consists in forming an elongated strip of metal having a recess for the reception of a stone or the like, and subsequently fastening the stone in the recess by bending the strip into ring form.

In testimony that I claim the foregoing as my own, I have hereto affixed my signature.

HENRY W. PETERS.
